UNITED STATES PATENT OFFICE

2,500,242

SHOE HOLDER AND STRETCHER

Claud E. Denton, Sallisaw, Okla.

Application October 15, 1948, Serial No. 54,656

3 Claims. (Cl. 12—128.6)

1

This invention relates to shoe supports and suspension means, and particularly to a shoe holder for individually supporting each shoe of a pair.

The main object of my invention is to provide means for supporting a shoe in suspended condition for restoring and maintaining its shape.

Another object is to provide means serving not only for supporting or suspending a shoe, but also for stretching the shoe when required.

A further object is to provide a shoe holder or support in the form of a projecting bracket adapted for attachment to a door, door post or wall, and serving to hold the shoe in suspended accessible position so that it may be cleaned and shined at will.

It is also an object to have a shoe holder of the indicated character which is adjustable to any size of shoe, and in addition, is capable of straightening and stretching the shoe mounted thereon to any extent desired.

A practical object is to make such a shoe holder light and simple in construction so as to be readily handled and obtainable at a reasonable cost, while not likely to get out of order.

Other objects and advantages of the invention will appear in further detail as the specification proceeds.

In order to facilitate ready comprehension of this invention for a proper appreciation of the salient features thereof, the invention is illustrated on the accompanying drawings forming part hereof, and in which:

Figure 1 is a side elevation of a shoe holder and stretcher made according to the invention and embodying the same in a practical form, the holder being shown as attached to a wall and supporting a shoe in suspended condition;

Figure 2 is a plan view of the shoe holder and stretcher of Figure 1, as seen from above in the latter figure, the shoe being omitted to clarify the view;

Figure 3 is a section taken on line 3—3 in Figure 2;

Figure 4 is a fragmentary section partially duplicating a portion of Figure 3, and showing the heel member of the latter in a different position than as shown in Figure 3;

Figure 5 is a similar fragmentary section showing the mentioned heel member in a different position than that of Figure 4;

Figure 6 is a plan view of the heel member of Figures 3, 4 and 5, as seen from above.

In the various views, the same reference numerals indicate the same or like parts.

2

When shoes are taken off, they are usually placed on the floor, in a clothes closet, or on a shelf, etc., and allowed to remain in whatever shape they have acquired in use and to dry and cool off in more or less bent or distorted condition. Aside from tending to retain the acquired shape, the shoes also frequently shrink a little while cooling and drying. Moreover, if the shoes are to be cleaned and shined before again being used, this is done by the troublesome method of holding and dealing with the shoes one at a time in time-honored fashion. Occasionally, shoe trees are inserted into the shoes individually to restore and retain proper shape therein, but even then the shoes with the shoe trees are simply placed on the floor or on a rack or shelf, but this scarcely facilitates cleaning and polishing the shoes thus equipped, as they must still be handled in substantially the same way and are then even heavier than when not provided with shoe trees. Should the shoes require stretching, such an operation must be performed by a special and independent device beyond the scope of an ordinary shoe tree.

Upon considering this problem, it has occurred to me that means should be available for supporting a pair of shoes out of contact with the floor and in position where they will be first of all accessible for cleaning and polishing the same, and then also definitely held in proper shape, and also adjustably fitted upon the supporting means whatever the size of the shoe involved, not to mention that it would seem highly desirable to have the shoe support capable in each case of stretching the shoe if required. As a result, I have succeeded in producing a suspension holder or support and stretcher for shoes, as will now be particularly explained and described.

Hence, in the practice of my invention, and referring again to the drawing, a shoe holder, generally indicated at 1, primarily includes a forwardly and downwardly-bent bracket 8 which consists of two bracket members 9, 10 having the upper end portions 11, 12 thereof diverging and terminating in a pair of attachment lugs 13, 14 attached to a wall or the like 15 by means of screws 16, 16. In order to fix the bracket 8 and both bracket members 9, 10 thereof rigidly in place, an upwardly-inclined brace 17 having an attachment lug 18 at the lower end thereof is secured by a further screw 16 to wall 15, while the upper end 19 is twisted into a vertical plane and is secured to members 9 and 10 by means 55 of a rivet 20.

Both bracket members 9 and 10 are arched downwardly to form a pair of downwardly-inclined bracket or rack members 21 and 22 terminating at the lower ends thereof in a pair of forwardly-projecting ends 23, 24, while upon said inclined members 21 and 22 immediately above the junction thereof with the forwardly-projecting ends 23 and 24 is mounted a wooden shoe block 25 upon a rivet 26, the block having a rearwardly-open slot 27 which extends a limited distance forwardly and upwardly from the lower surface 28 of block 25. Between projections 23 and 24 is a strip of leather 29 secured by nails or pins 30, 30 to the inside of block 25 within slot 27. The purpose of leather strip 29 is to frictionally hold block 25 in the normal operative position best seen in Figure 3, while, however, allowing upward swiveling of the front end or toe portion 31 thereof when required.

Through the intermediate inclined portions of bracket members 21 and 22 a bell crank lever 32 is pivotally mounted upon a pivot pin 33 extending through both bracket members 21 and 22, this bell crank lever having a downwardly and rearwardly-extending arm 34 upon which is pivotally mounted a heel block 35 by means of a pivot pin 36 passing through the lower end 37 of lever arm 34 extending into a forwardly-open slot 38 in the heel block. At the lower portion slot 38 is cut rearwardly at an angle, as indicated at 39 in Figures 3 and 4, to provide clearance for the lower end 37 of lever arm 34 in order to allow the heel block to swing into the extending position shown in Figure 5. In the upward direction, slot 38 is cut rearwardly at 40, as best seen in Figures 3 and 5, so that the block may swing forwardly into the position shown in Figure 4, the various positions assumed by the heel block facilitating introduction of the block into the heel portion 41 of a shoe 42 and releasing the device therefrom, the side and rear portions of block 35 being well rounded, as indicated at 43, to fit the interior of the heel portion 41 of the mentioned shoe. It is noted that the heel block 35 is disposed at a slightly higher level than shoe block 25 previously described, so that the bottom 44 of the block will be located immediately above the heel 45 of shoe 42 which is obviously higher than the sole 46 of said shoe.

In order to adjust heel block 35 according to the size of the shoe to be held by the device, and also to be in a position to stretch the shoe when required, as well as merely to hold it rigidly in position for cleaning and polishing the shoe, bell crank lever 32 has an upper short arm 47 to the end of which is pivoted the yoke 48 by means of a pivot pin 49. Through the upper portion of the yoke extends a round extremity 50 of a feed screw 51 with an end flange or collar 52 fixed upon the end thereof within the yoke and a second collar or flange 53 fixed upon screw 51 above the yoke in such fashion that rotation of the feed screw will cause simultaneous rotation of the flanges or collars 52 and 53 below and above the upper portion of the yoke. The feed screw extends upwardly through an internally-threaded swivel block 54 and terminates a distance above the latter with a manually-operable wing handle 55 secured upon the feed screw by means of a pin 56 and provided with the wings or finger pieces 57, 57 by which to rotate feed screw 51 at will. The swivel block 54 is provided on the opposite sides thereof with a pair of aligned trunnions 58 extending through the upper sections of the inclined portions 21 and

22 of the bracket members so that swivel block 54 is virtually rotatably mounted between bracket members 21 and 22.

The arrangement is such that by screwing down feed screw 51, the upper short arm 47 of bell crank lever 32 will be rotated about pivot pin 33 clockwise, thereby swinging the relatively longer lower arm 34 toward the left and thus causing heel block 35 to approach the shoe block 25 to a sufficient extent to allow shoe block 25 to be introduced into the mentioned shoe 42 and the forward toe portion 31 thereof thrust forwardly above sole 46 into the toe end 59 of the shoe virtually by moving the shoe rearwardly upon the block with the heel 45 extending rearwardly downward, and when the shoe block 25 is fully inserted, the heel portion 41 of the shoe is brought upwardly about heel block 35 until the lower end 44 thereof engages upon the interior heel portion 60 of the shoe above heel 45. While the shoe is thus held by the hand in position, the adjusting screw 51 is rotated in reverse direction by upper handle 55 in such fashion as to raise the short arm 47 of bell crank lever 32, whereby the lower arm 34 of the bell crank lever is moved rearwardly away from shoe block 25, causing the outer end 43 of the heel block 35 to engage against the interior of heel portion 41 of the shoe and simultaneously causing the shoe block to become tightly wedged in the forward portion 61 of shoe 42. As the bracket and the shoe and heel blocks, as well as the shoe 42 mounted thereon, thus temporarily form a rigid unit, it is a simple matter to brush off, shine and polish the shoe. Both hands are thus free to work in polishing the shoe, and the latter is held firmly without danger of slipping off or losing position. If a pair of shoes are to be mounted as already described in connection with shoe 42, and the same stored and not simply held for polishing and shining, a pair of brackets such as described in connection with the mentioned shoe 42 may be used, and when each shoe is firmly set into position on the blocks of each bracket, the shoe is held perfectly straight and in tense condition so that by the time it has cooled off and then dried, or until it is again to be used, the shoe will have been fully restored to proper condition and shape. It is likewise true that if desired a shoe mounted upon the bracket may be stretched, as for example, after the shoes have been wet by rain or snow and thereafter have become stiff and perhaps have shrunk in addition, it is but necessary to mount each shoe on the bracket and by adjusting screw 51 by means of handle 55, the shoe block and heel block may be so forcibly separated as to stretch the shoe back into shape and original length due to the swinging of lower lever arm 34 away from the forwardly-located shoe block 25 by rotating feed screw 51 or adjusting screw 51 counter-clockwise, if it is assumed that it is a right-hand screw.

When the shoe is to be released from the device, clockwise rotation of the feed screw 51 by handle 55 will cause the yoke in which the lower end 50 of adjusting screw 51 is rotatably mounted to rotate bell crank lever 32 clockwise, and as this causes the lower arm 34 thereof to approach the shoe block 25, the distance between shoe block 35 and block 25 will be decreased to a sufficient extent to allow the shoe heel portion 41 to be lowered away from heel block 35 when the shoe may be simply drawn forwardly off the shoe block 25.

While I have described the shoe block 25 and heel block 35 as made of wood, they can also be

made of plastic or metal, while the bracket members and the brace, as well as the bell crank lever and adjusting screw and other appurtenances may preferably be made of metal, but in any event the principles of the device remain the same whatever material is used for making the parts thereof.

Manifestly, variations may be resorted to and parts and features may be modified or used without others within the scope of the appended claims.

Having now fully described my invention, I claim:

1. A shoe support and stretcher including a bracket having means adapted for attachment to a wall and projecting forwardly and downwardly from the wall, a shoe-supporting block having a toe portion and mounted upon the lower portion of the bracket with the toe portion adapted to extend into the forward end of a shoe, a swivel block pivotally mounted upon the bracket above and spaced from the shoe-supporting block mounting and having a threaded hole extending therethrough, a lever pivotally mounted at one portion thereof upon said bracket a distance from the swivel block, a yoke pivotally mounted upon one end of the lever and having a bearing hole in one portion thereof, a manually-operated adjusting screw extending through and meshing with the threaded hole in said swivel block and having a lower end engaging rotatably in the bearing hole in the yoke with means for retaining said lower end in association with said yoke, a heel block having a slot therein and pivotally mounted upon the other end of said lever with the latter end extending into the slot in said heel block, and a handle on the other end of said adjusting screw for manipulating the latter.

2. A shoe support and stretcher including a bracket comprising two bracket members spaced apart and having means adapted for attachment to a wall and projecting forwardly and downwardly from the wall, a forwardly-extending portion upon the lower end of each bracket member, a shoe-supporting block having a toe portion and pivotally mounted upon the lower portions of the bracket members with the toe portion adapted to extend into the forward end of a shoe, the shoe block having a downwardly and rearwardly-open slot into which the forwardly-extending end portions of the bracket members project, a swivel block pivotally mounted between the bracket members above and spaced from the shoe-supporting block mounting and having a threaded hole extending therethrough, a lever pivotally mounted at one portion thereof between said bracket members a distance from the swivel block, a yoke pivotally mounted upon one end of the lever and having a bearing hole in one

portion thereof, a manually-operated adjusting screw extending downwardly through and meshing with the threaded hole in said swivel block and having a lower end engaging rotatably in the bearing hole in the yoke with means for retaining said lower end in association with said yoke, a heel block having a forwardly-open slot therein and pivotally mounted upon the other end of said lever with the latter end extending into the slot in said heel block, and a handle on the other or upper end of said adjusting screw for manipulating the latter.

3. A shoe support and stretcher including a bracket comprising two bracket members spaced apart and having means adapted for attachment to a wall and projecting forwardly and downwardly from the wall, a forwardly-extending portion upon the lower end of each bracket member, a shoe-supporting block having a toe portion and pivotally mounted upon the lower portions of the bracket members in the rear portion of said block with the toe portion thereof adapted to extend into the forward end of a shoe, said shoe block having a downwardly and rearwardly-open slot into which the forwardly-extending end portions of the bracket members project, a swivel block pivotally mounted between the bracket members above and spaced from the shoe-supporting block mounting and having a threaded hole extending therethrough, a bell crank lever pivotally mounted at the angle portion thereof between said bracket members a distance from the swivel block having one arm disposed rearwardly above the other and the latter arm projecting rearwardly downward, a yoke pivotally mounted upon the end of the first-mentioned arm of said bell crank lever and having a bearing hole in one portion thereof, a manually-operated adjusting screw extending downwardly through and meshing with the threaded hole in said swivel block and having a lower rotatable end engaging in the bearing hole in the yoke with means for retaining said lower end in association with said yoke, a heel block having a forwardly-open slot therein and pivotally mounted upon the end of the last-mentioned or lower arm of said bell crank lever with the end of the latter arm extending into the slot in said heel block, and a handle on the other or upper end of said adjusting screw whereby to manipulate the latter, and a rearwardly and downwardly-inclined brace member secured at the upper end thereof to the bracket members intermediate the lug means and the swivel block and at the lower rear end having a lug secured to said wall.
